G. M. BROWNE

BOOMERANG

Filed March 28, 1922

INVENTOR
G. M. BROWNE
By *John Michael Browne*

UNITED STATES PATENT OFFICE.

GERALD MACLEAY BROWNE, OF LIVERPOOL, ENGLAND.

BOOMERANG.

Application filed March 28, 1922. Serial No. 547,434.

To all whom it may concern:

Be it known that I, GERALD MACLEAY BROWNE, a subject of the King of Great Britain and Ireland, and a resident of Liverpool, county of Lancashire, England, have invented a certain new and useful Improvement in Boomerangs, of which the following is a specification.

My invention relates to an improved standardized boomerang.

Present-day boomerangs as manufactured will not describe a complete circle nor stay in the air unless they are merely thrown horizontally as gliders, and the object of my invention is to provide a standard boomerang which when held in a perpendicular position and thrown in an horizontal direction will describe a complete and perfect circle and return at high speed, the boomerang staying in the air at about an even height whilst travelling in a perpendicular position.

In order that my said invention may be the more readily understood, reference is to be had to the following description and accompanying sheet of drawings, wherein:—

Figure 1 is a view showing the convex side of the improved boomerang.

Figure 2 is a view showing the flat side thereof.

Figures 3 and 4 are, respectively, sectional views taken on lines x, x and y, y of Figure 2.

In the several figures, which are illustrative of a boomerang for right-handed circles (right to left), like letters of reference indicate corresponding parts.

In carrying out the invention, the convex side a of the boomerang is left almost as it usually is, but the flat side b of said boomerang is, towards one end thereof, thinned

or tapered off with and without slight concavity from along the line c —Figures 2 and 3—down to the front edge d of said boomerang, whilst the other end is thinned or tapered off in the same way from along the line e down to the rear edge f of said boomerang, thus faintly indicating a screw or propeller action. This slight propeller shaping constitutes the sum and substance of the invention.

In use, the boomerang is grasped by one end sickle-wise and thrown in a perfectly perpendicular position with flat side to the right, and at about six feet from the ground, after the manner of throwing a ball, the boomerang maintaining its perpendicular position whilst travelling in the air.

The boomerang can be made for describing either right to left, or left to right circles, although thrown by the right hand, but a separate boomerang for either flight, but with exactly reverse positions of tapering and throwing, will be required. Either may be thrown successfully by a left or right-handed man.

I claim:—

A boomerang including a sickle shaped body of segmental cross-section throughout, and the flat side of said body being beveled off at the one end to the rear edge and at the other end being beveled off to the front edge, the said beveled off parts being fashioned somewhat concavely.

In testimony whereof I have affixed my signature hereto this 14th day of March, 1922.

GERALD MACLEAY BROWNE.

Witnesses:

HENRY J. GREGORY,
JAS. C. MCRAE.
